UNITED STATES PATENT OFFICE.

OSCAR H. JUNG, OF MILWAUKEE, WISCONSIN, ASSIGNOR TO ARROW FUSE & MFG. CO.,
OF MILWAUKEE, WISCONSIN.

CARTRIDGE-FUSE.

1,275,442.

Specification of Letters Patent. Patented Aug. 13, 1918.

Application filed May 19, 1917. Serial No. 169,638.

To all whom it may concern:

Be it known that I, OSCAR H. JUNG, a citizen of the United States, and resident of Milwaukee, in the county of Milwaukee and 5 State of Wisconsin, have invented certain new and useful Improvements in Cartridge-Fuses; and I do hereby declare that the following is a full, clear, and exact description thereof.

10 My invention relates to certain new and useful improvements in fuses, and refers to a fuse embodying somewhat the same principles as those embodied in my application filed March 8, 1917, Serial No. 153325.

15 The primary object of this invention is to produce an inexpensive and simply constructed refillable fuse in which the fusible strip is inclosed, and which will meet the strict requirements exacted of all approved 20 fuses by the Underwriters' Laboratories.

Another object is to provide a fuse of the knife blade type in which the fuse proper is contained within a casing of non-conducting material, which casing carries the attaching 25 blades.

A further object is the provision of such a fuse which will have novel means for attaching the ends of the fuse strip with the attaching blades, and which will have novel 30 means for securing the knife blades to the casing.

A still further object of my invention is the production of a device of the character and for the purpose described which will be 35 simple in construction, efficient and practical, and inexpensive to manufacture, all things being considered.

With the above and other objects in view which will appear as the description proceeds, my invention resides in the novel construction, combination and arrangement of parts substantially as hereinafter described and particularly defined by the appended 45 claims, it being understood that such changes in the precise embodiment of the herein disclosed invention may be made as come within the scope of the claims.

In the accompanying drawings I have illustrated one complete example of the

physical embodiment of my invention constructed according to the best mode I have so far devised for the practical application of the principles of my invention, in which:

Figure 1 is a sectional view taken longitudinally through a knife fuse embodying 55 my invention.

Fig. 2 is a sectional view taken on the plane indicated by line 2—2 of Fig. 1.

Fig. 3 is a transverse sectional view taken on the plane indicated by line 3—3 of Fig. 1, and

Fig. 4 is a perspective view of the yoke clamp employed to rigidly secure the knife blades to the outer casing.

Referring now more particularly to the 65 several figures of the drawing wherein similar reference characters designate like parts, the numeral 1 denotes a cylindrical tube of fiber or other non-conducting material and for closing the ends thereof, a pair of like 70 metallic caps 2 are employed provided each with a centrally disposed elongated slot 3 and a pair of smaller slots 4 disposed one on each side of said central slot.

Engaging the slots 3 are a pair of attaching blades 5 having their outer ends plain for engagement with the usual spring clip of a switch board (not shown) and their inner ends disposed inside of the caps 2 and provided near their inner edges with 75 recesses 6 to allow adjustment therein of threaded screws 7 employed for securing the caps 2 upon the casing 1.

The screws 7 also assist in retaining the knife blades 5 in the caps 2 and engage the 85 arms 8 of the yoke clamps 9, said yoke clamps being provided with portions 10 adapted to lay flush against the inner surface of the caps 2 having laterally turned arms 8 and then inwardly turned forked or 90 bifurcated portions 11, said bifurcated portion engaging the blades 5 as clearly shown in Fig. 1. The yoke clamps are thus in the form of substantially U-shaped plates having slotted base portions and inturned bifurcated end portions.

The yoke clamp 9 is adapted to be secured to the caps 2 and for this purpose is pro-

vided with a pair of laterally extending ears or lugs 12 adapted to be bent outwardly and then inwardly and engaging the slotted openings 4 as more clearly shown in Fig. 2. 5 Thus it will be seen that the knife blades 5 are rigidly, but detachably secured to the caps 2, forming a very desirable construction.

The fuse cartridge proper is disposed in 10 the casing 2 and consists essentially in the tubular casing 13 of non-conducting material having closing the ends thereof a pair of metallic caps 14 provided with ventilating openings 15 and elongated slots 16 through 15 which pass the fusible strip 17 having the usual reduced central portion 18 and being surrounded by a finely divided arc-choking material 10.

The ends of the fuse strip 17 extend outwardly of the caps 14 and are provided with 20 apertures 19 adapted to engage the bolt 20 which also engages a corresponding aperture 21 in the inner end of the blades 5. In this way the fuse strip is connected with 25 the blades 5 and to prevent shifting of the fuse strip within its container cotter pins 22 are employed disposed one at each cap 14.

Thus it will be seen from the foregoing description taken in connection with the 30 accompanying drawing that I have provided a fuse in which the fusible link will be readily interchangeable and one which accomplishes the desired objects without the complicated arrangement and construction 35 of the existing fuses of this type.

What is claimed is:

1. A device of the class described comprising an open end casing, a slotted cap for closing one end of the casing, an attaching 40 blade extending through the slot of the cap, a U-shaped plate having a slot in its base receiving said blade, the arms of the plate being secured to the casing, means carried by the arms for engaging the inner end of 45 said blade, and a fusible link secured to said blade.

2. A device of the class described comprising an open end casing, a slotted cap for closing one end of the casing, an attaching 50 blade extending through the slot of the cap, a U-shaped plate having a slot in its base receiving said blade, the arms of the plate being secured to the casing, the inner end of one of said arms being inturned and bifurcated, the inner end of said blade being disposed between the furcations, and a fusible link connected to the inner end of said blade.

3. A device of the class described comprising an open end casing, a slotted cap for closing one end of the casing, an attaching 60 blade extending through the slot of the cap, a U-shaped plate having a slot in its base receiving said blade, the arms of the plate

being secured to the casing, the inner ends 65 of said arms being bent inwardly toward each other and bifurcated, the furcations being engaged with the opposite edges of the inner end of said blade, and a fusible link secured to the inner end of the blade. 70

4. A device of the class described comprising an open end casing, a cap for closing one end of the casing, said cap having a central slot and relatively smaller slots disposed one on each side of said central slot, an attaching blade disposed through said central slot, a U-shaped plate having a slot in its base receiving said blade, means on the arms of the plate for engaging the inner end of the blade, lugs extending from the plate and 80 disposed in said relatively smaller slots in the cap, and a fusible link connected with the inner end of said blade.

5. A device of the class described comprising an open end casing, a cap for closing 85 one end of the casing, said cap having a central slot and relatively smaller slots disposed one on each side of said central slot, an attaching blade disposed through said central slot, a plate having a slot receiving 90 said blade, oppositely extending lugs on the plate, said lugs being disposed through said relatively smaller slots and bent laterally, means carried by the plate for engaging the inner end of the blade, and a fusible link 95 connected with the inner end of said blade.

6. A device of the class described comprising an open end casing, a slotted cap for closing one end of the casing, an attaching blade extending through the slot in the cap, the 100 opposite edges of said blade being notched, a U-shaped plate having a slot in its base receiving said blade, screws extending through the cap and the arms of said U-shaped plate and engaged with said notches 105 blade to limit every movement thereof, and a fusible link secured to the inner end of the blade.

7. An electrical fuse unit comprising, in combination, a non-conducting open ended 110 casing, metallic caps covering the ends thereof and provided each with a central elongated slot and relatively smaller slots disposed one on each side of said central slot, an attaching blade carried by each cap and 115 projecting through the central slots into the casing, a yoke clamp having lugs engaging the smaller slots and having their ends in-turned to clamp the inner ends of said blades and a fuse cartridge disposed within 120 said casing and having its fuse strip in connection with the inner ends of the attaching blades.

8. A device of the class described comprising an open end casing, a slotted cap for 125 closing one end of the casing, an attaching blade extending through the slot in the cap, the opposite edges of said blade being

notched, a U-shaped plate having a slot in its base receiving said blade, the inner ends of the arms of said plate being inturned and bifurcated to receive the inner end of said blade, screws extending through said caps and the arms of said U-shaped plate and engaged with said notches in the blade to limit outward movement of the latter, and a fusible link secured to the inner end of the blade. 10

In testimony that I claim the foregoing I have hereunto set my hand at Milwaukee, in the county of Milwaukee and State of Wisconsin.

OSCAR H. JUNG.
